UNITED STATES PATENT OFFICE.

ADOLPH SPIELMAN, OF PHILADELPHIA, PENNSYLVANIA.

WALL-SWITCH FOR DISTANT CONTROL OF GAS-SUPPLY.

1,240,895.

Specification of Letters Patent. Patented Sept. 25, 1917.

Application filed July 6, 1917. Serial No. 178,956.

To all whom it may concern:

Be it known that I, ADOLPH SPIELMAN, a citizen of the United States, residing at Philadelphia, in the county of Philadelphia and State of Pennsylvania, have invented a certain new and useful Improved Wall-Switch for Distant Control of Gas-Supply, of which the following is a specification.

The principal objects of the present invention are to provide a new and novel form of wall switch for the distant control of gas supply which is of simple and inexpensive construction; which is efficient and reliable in operation and which is reversible in character so that it may be adaptable for use in connection with a single gas fixture or a battery of gas fixtures. With these and other objects in view the invention consists of the improvements hereinafter described and finally claimed.

The nature, characteristic features and scope of the invention will be more fully understood from the following description taken in connection with the accompanying drawings forming part hereof, and in which:

Figure 1, is a view in elevation of the wall switch illustrating the application of the same to a gas chandelier.

Fig. 2, is a rear, detached view of the switch and

Fig. 3, is a view in section taken upon the line 3—3 of Fig. 2.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings there is shown, for the purpose of illustration, the application of the wall switch of the invention to a gas chandelier as used in a residence. Obviously, the switch is applicable for use in connection with other forms of gas fixtures or burners. In the drawings 10, designates a gas chandelier, 11 designates the usual gas inlet connection and 12 a pilot light connection. 13 designates a valve of a type adapted to be alternately turned off and on by similar successive movements of valve

operating means 14. The valve 13 and operating means 14 are contained within and concealed by the chandelier canopy 15 and the pilot tube 12 is concealed throughout the major portion of its length by the chandelier parts. In practice the valve 13 is provided with a rotary plug equipped with a toothed segment 16 and the valve operating means 14 which is pivotally disposed is provided with a toothed portion 17 for meshing therewith. These connections form part of separate and independent inventions, consequently, further description is not necessary in this case. The valve operating means 14 is connected by an arrangement of wiring with the wall switch 18 of the invention. Connecting the free end of the pivotal valve operating means 14 and one arm of a bell-crank lever 19 is a wire 20 and connecting the other arm of the bell-crank lever and the curved and pivotal arm 21 of the wall switch 18 is a wire 22. A spring 23 is connected to the free end of valve operating means 14 to insure the latter always returning to its position of rest, after movement of the wall switch lever 24, it being understood that the lever 24 also is returned to initial position by the spring 23. In practice the switch 18 is secured to a wall 25, and if desired the wiring may be concealed therebehind.

A detailed description of the switch 18 will now be given. 26 designates a flat plate of rectangular configuration apertured as at 27 for the passage therethrough of screws or the like for attaching the plate 26 to the wall 25. Pivoted to the rear of the plate 26 adjacent one of its narrow ends, as at 28, is an elongated lever 24 the free end of which is provided with an operating handle 29 the shank 31 of which is projected through and works in a slot 30 formed upon an arc of a circle adjacent the end of the plate opposite the pivot point of the lever 29. The free end of the shank 31 is burred as at 32 and the handle is provided with a shoulder 33 so that said handle is afforded a snug sliding fit with respect to the plate 26. In this connection it is to be observed (see Fig. 3) that the respective ends of the lever 24 are bent over as at 34 so that the major portion of the lever is spaced from the back of plate 26. Fixed to and projected rearwardly from the plate 26 is a stud 35 mounted upon which is an eccentric 36 preferably having formed integral therewith the arm 21, the end of

which is apertured as at 21' to receive the wire 22. The head of the stud 35 and the eccentric 36 are positioned so as to lie between the plate 26 and lever 24. The eccentric 36 has formed peripherally thereof a notch 37 which engages at all times a pin 38 fixed to the lever 24. A lever so arranged and constructed provides for a maximum movement at the valve plug by a minimum movement of the lever 24.

A switch constructed as above described may be readily stamped from metal. But few and very simple and inexpensive parts are present; it is efficient in use and may be attached to a wall in any desired position, being reversible in character; is positive in action and has no delicate connections to get out of order and has therefore commercial value in the gas industry.

It will now be apparent that I have devised a novel and useful construction which embodies the features of advantage enumerated as desirable in the statement of the invention and the above description and while I have in the present instance shown and described the preferred embodiment thereof which has been found in practice to give satisfactory and reliable results, it is

to be understood that the same is susceptible of modification in various particulars without departing from the spirit or scope of the invention or sacrificing any of its advantages.

What I claim is:—

1. An article of the character stated embracing a wall plate having a slotted portion adjacent one end thereof, a lever pivoted adjacent the other end of said plate, the respective ends of said lever abutting against said plate and at least a portion of the intermediate part of the lever being spaced from the plate, an operating handle secured to the lever and projected through the slot in said plate, an eccentric having an outwardly extended arm pivoted to said plate so as to lie between the plate and said lever, and means for connecting the lever to said eccentric.

2. An article as described in claim 1 characterized by the eccentric having a slot in its periphery to accept a pin fixed upon the operating lever.

In testimony whereof I have hereunto signed my name.

ADOLPH SPIELMAN.
